UNITED STATES PATENT OFFICE.

RENSELAER R. MOORE, OF CORTLAND, NEW YORK.

IMPROVEMENT IN GUN-BARRELS.

Specification forming part of Letters Patent No. 122,187, dated December 26, 1871.

To all whom it may concern:

Be it known that I, RENELAER R. MOORE, of Cortland, in the county of Cortland and State of New York, have invented a new and useful Improvement in Shot-Gun; and I do hereby declare that the following is a full and exact description of the same, reference being had to the accompanying drawing and to the letters of reference marked thereon.

This invention relates to that class of shot-guns which are provided with a contracted muzzle for the purpose of concentrating the charge as it leaves the gun; and consists in forming the contraction in the muzzle itself by swaging the end into suitable form, as will be fully described hereinafter.

In the drawing, Figure 1 represents a perspective view of the machine employed for contracting the muzzle with a gun-barrel in position; and Fig. 2 represents a central vertical elevation of the same.

To enable others skilled in the art to make and use my invention, I will now proceed to describe fully its construction and manner of operation.

Shot-guns that have been provided heretofore with a contracted muzzle for concentrating the charge as it leaves the gun, have either been furnished with an auxiliary thimble screwed to the gun or have had the ends of the barrel cut and the parts between the cuts drawn together by a tapering screw-socket. These methods are objectionable because the auxiliary devices naturally increase the expense of the gun, and because, also, they necessarily occupy more or less space outside of the line of the barrel, so that it is impossible to use them on double-barrelled guns. My invention consists in forming the con-

traction in the barrel itself, after the same has been bored and trimmed, which result is accomplished by forcing the end of the barrel into a properly-formed socket with sufficient power to give it the requisite shape. A suitable machine for this purpose is shown in the drawing.

a represents any suitable base block, provided with standards *b c*, one of which, *b*, is provided with a tapering socket, *d*, of proper form, as shown in the drawing; the other standard *c* has an opening, *e*, for the reception of the gun-barrel, which opening is in direct line with the socket *d*.

The operation is as follows: The gun-barrel to be operated upon is passed through the opening in standard *c* and its muzzle is thrust into the socket *d*. Sufficient force is now applied to it in any proper manner to upset the metal and cause it to assume a tapering form, as indicated in Fig. 2. By means of this operation the desired contraction is solidly formed in the barrel itself, and instead of being weakened thereby, as is the case with the usual methods of producing this result, the parts are strengthened to resist the strain to which they are subjected.

Having thus fully described my invention, what I claim as new, and desire to secure by Letters Patent, is—

As a new article of manufacture, a gun-barrel having a contracted muzzle formed in the metal of the barrel itself, substantially as described.

This specification signed and witnessed this 10th day of November, 1871.

RENSELAER R. MOORE.
